HYDRAULICALLY RETARDED DOOR CLOSER
George R. Millard, Tekonsha, and Bruce B. Bideleman
and William L. Nobbs, Marshall, Mich., assignors to
Ronan and Kunzl, Incorporated, Marshall, Mich.

Filed May 4, 1961, Ser. No. 107,776
10 Claims. (Cl. 16—52)

This invention relates to improvements in hydraulically retarded door closer. The principal objects of this invention are:

First, to provide an improved form of door closer of the spring actuated hydraulically regulated cylinder type in which the retracting, door closing motion of a spring pressed piston is controlled through three different stages or rates of travel by means of hydraulic regulating valves actuated automatically by travel of the piston.

Second, to provide valve mechanism for a hydraulic door closer which is relatively simple and in which the relatively small regulating parts are self cleaning so that dirt particles in the hydraulic fluid will not clog the mechanism.

Third, to provide a hydraulic door closer with an automatic safety release which will relieve the hydraulic retarding pressure when a predetermined maximum pressure is created as for example, by manual closing of the door at a faster rate than the normal closing rate of the mechanism.

Fourth, to provide novel valve means in a hydraulic door closing cylinder which are easily assembled and reliable in operation in that there is little chance for the operating parts to get out of adjustment.

Fifth, to provide a regulatory valve system for a hydraulically retarded door closing piston in which a cavity formed in the piston first moves into cooperating engagement with a yieldable hollow valve pin to form a first restriction impeding the flow of fluid through the valve pin and thus creating a first retarding force on the retracting piston after which the yieldable valve pin is retracted by the piston to progressively close off a second restricted passage and thus create a second and further retarding action on the retracting motion of the piston; the yieldable support of the hollow valve pin further functioning as a safety release to disengage the valve pin from the chamber in the piston upon creation of excess pressure to reopen the full flow of fluid from the piston chamber.

Other objects and advantages of the invention will be apparent from a consideration of the following description and claims. The drawings, of which there is one sheet, illustrate a highly practical form of the invention.

FIG. 1 is a fragmentary elevational view of a door with the door closer of the invention operatively associated therewith.

FIG. 2 is a fragmentary longitudinal cross sectional view through the cylinder and valve connections of the closer taken along the plane of the line 2—2 in FIG. 1 and illustrating the mechanism during door opening motion of the door.

FIG. 3 is a fragmentary enlarged cross sectional view similar to FIG. 2 but showing the mechanism in the fully closed position of the door.

FIG. 4 is a fragmentary transverse cross sectional view through the door closer cylinder and piston taken along the plane of the line 4—4 in FIG. 2.

FIG. 5 is a transverse cross sectional view through the end block of the cylinder taken along the plane of the line 5—5 in FIG. 2 and illustrating the manual adjusting valve of the closer.

FIG. 1 illustrates the relationship of the door closer of the invention to the door which it is arranged to control. As shown in FIG. 1 a swinging door 1 is mounted in a doorway 2 with the door closing cylinder 3 of the in-

2

vention mounted in the space which already exists in the usual header of the door frame. The cylinder 3 is provided with a reciprocable piston rod 4 which is actuated by a suitable cam or crank mechanism indicated generally at 5 to withdraw or advance the piston rod from the cylinder when the door is opened and to control the retraction of the piston rod into the cylinder under spring pressure as will be described to regulate the closing motion of the door. The cam or crank mechanism 5 has a drive pin 6 which is connected to the door to couple the door to the closer mechanism. Details of the crank or cam mechanism 5 are not disclosed as a variety of door closing cams and cranks are well known in the prior art and can be utilized in combination with the piston rod 4.

As appears more clearly in FIGS. 2 to 5, the door closer cylinder 3 is provided with a rear end block 7 and a front end block 8 considering the front of the cylinder as the end from which the piston rod 4 extends. One of the end blocks, in this case the front end block 8, is provided with mounting flanges 9 for securing the cylinder to a suitable support located in the space within the header of the door frame. The piston rod 4 carries a piston 11 at its inner end and both the piston and the piston rod are urged inwardly of the cylinder by a relatively heavy door closing spring 12 engaged with the abutment ring 13 on the piston rod and the inner side of the front end block 8. Upon inward retracting motion of the piston and piston rod toward the left as viewed in FIG. 2, hydraulic fluid hereafter referred to as oil, is displaced by the piston 11 through the hollow valve pin 14 to passages in the rear end block 7 from which the oil is delivered past a manually adjustable metering pin 15 to the passage 16 and return pipe 17. The pipe 17 connects with the front block 8 and passages 18 therein to return the oil to the opposite or front side of the piston.

Considering in greater detail the construction of the piston 11 and its mounting on the piston rod 4, it will be noted that the piston has a cylindrical body with a groove therearound for the seal ring 19. The center of the piston 11 defines a bore slidably receiving the reduced inner end portion 20 of the piston rod 4. A pin 21 passed diametrically through the piston is loosely received in an oversized bore 22 in the piston rod permitting the piston to shift axially along the piston rod. The side of the reduced portion 20 of the piston rod is flattened or cut away as at 23 (see FIG. 4) forming a passage completely along the side of the reduced portion and through the piston so that when the piston rod moves outwardly to the right as shown in FIG. 2, the outer face of the piston 11 moves relatively inwardly away from the shoulder 24 on the piston rod exposing the outer end of the flattened area 23 and oil can be displaced from the right hand end of the cylinder 3 along the flat 23 to the left hand side of the piston. Upon inward motion of the piston rod the resistance of the oil against the inner face of the piston moves the piston against the shoulder 24 and prevents return flow of oil through the center of the piston. The piston and piston rod thus form a one way check valve for introducing oil to the left side of the cylinder.

On its right side the piston 11 carries a cylindrical flange 25 to which is secured a short cylindrical wire screen 26 with a bushing 27 on its outer end which slides on the piston rod 4. The inner end of the piston rod 4 projects through the piston 11 and has a short bore or recess 28 formed therein coaxially with the valve pin 14. The recess 28 cooperates with the regulating valve 14 as will be described in greater detail.

Considering the rear end member 7 and the regulating valve 14 in greater detail, it will be noted that the end member defines a central bore or chamber 29 which communicates at its rear end with the bore 30 and in turn with the stepped lateral bore 31 within which the manual-

ly adjustable needle valve 15 is mounted. The outer or right end of the end member 7 defines a counterbore 32 around the end of the chamber 29 and a very fine inclined notch 33 is cut in the shoulder between the bore 29 and the counter bore 32. The hollow tubular needle valve 14 has an enlarged shoulder 34 which fits slidably and sealingly in the chamber or bore 29 with a spring 35 bearing against the inner end of the needle valve and pressing the shoulder axially outwardly against a retaining ring 36 pressed into the counter bore 32. The outer elongated end of the needle valve is passed guidingly but in nonsealing relation through the retaining ring 36.

The outwardly projecting right end of the tubular needle valve 14 is tapered as at 37 so as to have a self-centering engagement with the recess 28 in the piston rod and the tapered end of the needle valve is provided with a small calibrated notch 38 forming a small controlled opening into the chamber 28 and the outer end of the needle valve when the inner end of the piston rod is pressed inwardly over the outer end of the needle valve as shown in FIG. 3.

From the foregoing description of the structure of the cylinder and valve mechanisms it will be apparent that when the piston rod and piston have moved fully to the right as viewed in FIG. 2 most of the oil is displaced into the left end of the cylinder. In being so displaced the oil passes through the screen 26 before it reaches the passage along the flat 23 on the piston rod where the rod passes through the piston. Subsequent inward retracting motion of the piston rod caused by expansion of the spring 12 and closing motion of the door will first displace oil freely from the left end of the cylinder through the exposed open end of the hollow needle valve 14, chamber 29, passages 30 and 31 and past the adjusting valve 15 to the return tube 17 from where the oil reenters the right side of the cylinder. The initial displacement is relatively unobstructed and is controlled primarily by the adjusting valve 15. Initial closing motion of the door by the spring 12 and piston rod 4 is accordingly relatively rapid. As the piston 11 approaches the hollow needle valve 14 the tapered end of the valve enters the recess 28 so that any continued displacement of oil must be through the metering notch 38 in the end of the needle valve and through the small metering notch 33 at the outer end of the valve chamber 29 in the end member 7. The combined oil flow through these two metered passages constitutes a first reduced flow to impose a first degree of restriction to further inward motion for the piston 11. As the piston continues inwardly at the first reduced rate of travel, the hollow needle valve is pressed rearwardly or inwardly by engagement with the piston rod around the recess 28 so that the enlarged portion 34 around the needle valve moves inwardly beyond the notch 33 as is shown in FIG. 3 thus cutting off the flow through the notch 33 and creating a second reduction and a second degree of increased resistance to inward motion of the piston. All oil displaced by final inward motion of the piston rod and piston must flow through the first reduced passage 38 and through the hollow tubular needle valve to the return pipe 17. The final closing motion of the door is thus slowed to a minimum to prevent objectionable slamming.

Should the pressure created in the left end of the cylinder 3 by inward movement of the piston 11 be raised substantially above the normal pressure created by the spring 12, this increased pressure acts against the outer face of the enlarged portion 34 of the needle valve and compresses the needle valve against the pressure of spring 29 to retract the needle valve further than the recess or cavity 28 thus reopening the outer end of the tubular needle valve to the left end of the cylinder 3. This reopening of the needle valve reduces the resistance to inward motion of the piston permitting relief of excess pressure through the needle valve and in addition permitting more rapid inward motion of the piston rod and piston.

The hollow needle valve 14 with its enlarged portion 34 and the spring 29 thus constitute a safety relief valve cooperating with the piston 11 to permit more rapid closing of the door 2. The safety valve arrangement will become operative, for example, should a person push the door closed at a faster rate than the normal closing rate of the return spring 12. The safety valve prevents the building up of excess pressures in the left end of the cylinder 3 which might damage other parts of the system and also permits the door to be closed manually at a faster rate than by the closing spring without forcing the door against the normal restraining pressure in the left end of the cylinder. It is a feature of the valve system that the two primary restricted passages formed by the notches 33 and 38 are opened regularly by each operation of the door and are thus self cleaning as oil is forced over the notches. It, therefore, is practically impossible for the metering passages to become clogged and inoperative.

What is claimed as new is:

1. Door closer mechanism including in combination a cylinder having inner and outer end members with a piston rod projecting through the outer end member, an oil return pipe extending between said end members and communicating through return passages in the end members with opposite ends of said cylinder, a manually adjustable regulating valve in one of said passages, a piston in said cylinder connected to said rod for reciprocation by the rod, a spring biasing said rod inwardly into said cylinder, means providing a limited sliding engagement between said piston and said rod, and a passage formed by a flattened area on the rod uncovered by inward displacement of the piston relative to the rod forming an inwardly opening and outwardly closing check valve through said piston, a bore formed in the inner end member as part of the return passage therethrough, a hollow needle valve having an enlarged portion slidably and sealingly received in said bore, a second spring biasing said needle valve outwardly of said bore, a groove in the wall at the outer end of said bore forming a first restricted passage past said enlarged portion of said needle valve in the outwardly projected position of the needle valve, a recess formed in the inner end of said rod positioned to receive and substantially close the hollow outer end of the needle valve in an inwardly retracted position of said rod, the end of said needle valve being tapered to enter into said recess and having a small groove in the tapered surface of the valve cooperating with the wall of the recess to form a second restricted passage to the end of the hollow needle valve when said piston is retracted over said needle valve.

2. Door closer mechanism including in combination a cylinder having inner and outer end members with a piston rod projecting through the outer end member, an oil return pipe extending between said end members and communicating through return passages in the end members with opposite ends of said cylinder, a piston in said cylinder connected to said rod for reciprocation by the rod, a spring biasing said rod inwardly into said cylinder, means providing a limited sliding engagement between said piston and said rod, and a passage uncovered by inward displacement of the piston relative to the rod forming an inwardly opening and outwardly closing check valve through said piston, a bore formed in the inner end member as part of the return passage therethrough, a hollow needle valve having an enlarged portion slidably and sealingly received in said bore,

a second spring biasing said needle valve outwardly of said bore,
 means forming a first restricted passage past said enlarged portion of said needle valve in the outwardly projected position of the needle valve,
 a recess formed in the inner end of said rod positioned to receive and substantially close the hollow outer end of the needle valve in an inwardly retracted position of said rod,
 the end of said needle valve having a small groove in 10 the tapered surface of the valve cooperating with the wall of the recess to form a second restricted passage to the end of the hollow needle valve when said piston is retracted over said needle valve.
 3. Door closer mechanism including in combination a 15 cylinder having inner and outer end members with a piston rod projecting through the outer end member, a fluid return pipe extending between the inner one of said end members and the other end of said cylinder and communicating through a return passage in 20 said one end member with opposite ends of said cylinder, a manually adjustable regulating valve in said passage, a piston in said cylinder connected to said rod for reciprocation by the rod, 25 a spring biasing said rod inwardly into said cylinder, means providing a limited sliding engagement between said piston and said rod, and a passage uncovered by inward displacement of the piston relative to the rod forming an inwardly opening and outwardly closing check valve through said piston,
 a bore formed in the inner end member as part of the return passage therethrough,
 a hollow needle valve having an enlarged portion slidably and sealingly received in said bore, 30 a second spring biasing said needle valve outwardly of said bore,
 a groove in the wall at the outer end of said bore forming a first restricted passage past said enlarged portion of said needle valve in the outwardly projected position of the needle valve,
 a recess formed in the inner end of said rod positioned to receive and substantially close the hollow outer end of the needle valve in an inwardly retracted position of said rod, 35
 the end of said needle valve being adapted to enter into said recess and cooperating with the wall of the recess to form a second restricted passage to the end of the hollow needle valve when said piston is retracted over said needle valve.
 4. Door closer mechanism including in combination a 40 cylinder having inner and outer end members with a piston rod projecting through the outer end member, a fluid return pipe extending between the inner one of said end members and the other end of said cylinder and communicating through a return passage in said one end member with opposite ends of said cylinder, 45 a recess formed in the inner end of said rod positioned to receive and substantially close the hollow outer end of the needle valve in an inwardly retracted position of said rod, the end of said needle valve being cooperative with the end of said rod to form a restricted passage to the end of the hollow needle valve when said piston is retracted against said needle valve.

5. Door closer mechanism including in combination a cylinder having inner and outer end members with a piston rod projecting through the outer end member, a fluid return pipe extending between the inner one of said end members and the other end of said cylinder and communicating through a return passage in said one end member with opposite ends of said cylinder, a piston in said cylinder connected to said rod for reciprocation by the rod, a spring biasing said rod inwardly into said cylinder, means forming an inwardly opening and outwardly closing check valve through said piston,
 a bore formed in the inner end member as part of the return passage therethrough,
 a hollow needle valve having an enlarged portion slidably and sealingly received in said bore, a second spring biasing said needle valve outwardly of said bore, the inner end of said rod being adapted to abut and substantially close the hollow outer end of the needle valve in an inwardly retracted position of said rod, the end of said needle valve being cooperative with the end of said rod to form a restricted passage to the end of the hollow needle valve when said piston is retracted against said needle valve.
 6. Door closer mechanism including in combination a cylinder having inner and outer end members with a piston rod projecting through the outer end member, a fluid return pipe extending between the inner one of said end members and the other end of said cylinder and communicating through a return passage in said one end member with opposite ends of said cylinder, a piston in said cylinder connected to said rod for reciprocation by the rod, a spring biasing said rod inwardly into said cylinder, means forming an inwardly opening and outwardly closing check valve through said piston,
 a bore formed in the inner end member as part of the return passage therethrough,
 a hollow needle valve slidably and sealingly received in said bore, a second spring biasing said needle valve outwardly of said bore, the inner end of said rod being adapted to abut and substantially close the hollow outer end of the needle valve in an inwardly retracted position of said rod, the end of said needle valve being cooperative with the end of said rod to form a restricted passage to the end of the hollow needle valve when said piston is retracted against said needle valve.
 7. Door closer mechanism including in combination a cylinder having inner and outer end members with a piston rod projecting through the outer end member, a fluid return pipe communicating through a return passage in the inner one of said end members with opposite ends of said cylinder, a piston in said cylinder connected to said rod for reciprocation by the rod, a spring biasing said rod inwardly into said cylinder, means providing a limited sliding engagement between said piston and said rod, and a passage uncovered by inward displacement of the piston relative to the rod forming an inwardly opening and outwardly closing check valve through said piston,
 a bore formed in the inner end member as part of the return passage therethrough,
 a hollow needle valve having an enlarged portion slidably and sealingly received in said bore, a second spring biasing said needle valve outwardly of said bore, and means forming a restricted passage past said en-

larged portion of said needle valve in the outwardly projected position of the needle valve,
a recess formed in the inner end of said rod positioned to receive and substantially close the hollow outer end of the needle valve in an inwardly retracted position of said rod. 5

8. Door closer mechanism including in combination a cylinder having inner and outer end members with a piston rod projecting through the outer end member, a fluid return pipe communicating through a return passage in the inner one of said end members with opposite ends of said cylinder, a piston in said cylinder connected to said rod for reciprocation by the rod, a spring biasing said rod inwardly into said cylinder, 15 means forming an inwardly opening and outwardly closing check valve through said piston, a bore formed in the inner end member as part of the return passage therethrough, a hollow needle valve having an enlarged portion 20 slidably and sealingly received in said bore, a second spring biasing said needle valve outwardly of said bore, and means forming a restricted passage past said enlarged portion of said needle valve in the outwardly projected position of the needle valve, 25 said rod being arranged to substantially close the hollow outer end of the needle valve in an inwardly retracted position of said rod.

9. Door closer mechanism including in combination 30 a cylinder having inner and outer end members with a piston rod projecting through the outer end member, a fluid return pipe forming a return passage extending between the inner one of said end members and the opposite end of said cylinder, 35 a piston in said cylinder connected to said rod for reciprocation by the rod, a spring biasing said rod and piston inwardly into said cylinder, means forming an inwardly opening and outwardly 40 closing check valve through said piston, a bore formed in the inner end member as part of the return passage therethrough, a hollow needle valve slidably and sealingly received 45 in said bore,

a second spring biasing said needle valve outwardly of said bore, said rod being arranged to substantially close the hollow outer end of the needle valve in an inwardly retracted position of said rod.

10. In a hydraulically retarded door closer having a cylinder member and a piston member reciprocable therein and spring biased to a retracted position, said members being adapted to be connected between a fixed point and a door to reciprocate relative to each other with movement of the door, means including a one way check valve forming a first passage between the opposite ends of said cylinder and through said piston member, means forming a second passage between the opposite ends of said cylinder and including a bore formed in one end of said cylinder and a conduit communicating with the bore and the other end of said cylinder, means for varying the effective size of said second passage including a hollow tubular needle valve axially slidably mounted in one of said members and engageable with the other of said members near the end of the retracting motion of the members, said other of said members having a seat formed thereon engaged by said valve and coacting therewith to form a substantial closure on said seat with a small metered opening therebetween between the interior of said cylinder and said second passage through said hollow needle valve, and a spring acting between said valve and said one of said members urging said valve toward said other of said members, said valve and said one member in which it is mounted defining a second metered opening from said cylinder to said second passage which is open in the extended position of the valve and closed when said valve is pushed in against said spring.
